SPINNING RING AND SECURING DEVICE
THEREFOR

George West, Whitinsville, Mass., assignor to
Whitin Machine Works, Whitinsville, Mass., a
corporation of Massachusetts

Application January 29, 1936, Serial No. 61,343

3 Claims. (Cl. 118—59)

This invention relates to spinning or twisting frames and particularly to means for securing a spinning or twisting ring in a ring rail.

The invention is particularly designed for use 5 in connection with ring rails produced from sheet metal by pressing or other forming operations.

It has not been found practical to secure a ring in such a sheet steel ring rail by using the attaching means heretofore commonly used with 10 cast iron ring rails, on account of the comparative thinness of the sheet steel rail.

It is the general object of my invention to provide an improved device for securing a spinning or twisting ring or a ring holder in a ring rail 15 formed of sheet metal of relatively small thickness.

My invention further relates to arrangements and combinations of parts which will be herein-after described and more particularly pointed out in the appended claims.

20 A preferred form of the invention is shown in the drawing, in which

Fig. 1 is a plan view of a portion of a ring rail with a twister ring mounted therein;

25 Fig. 2 is a transverse sectional elevation, taken along the line 2—2 in Fig. 1;

Fig. 3 is an enlarged sectional elevation, taken along the line 3—3 in Fig. 2;

Fig. 4 is a plan view of a portion of a ring rail 30 having a spinning ring and ring holder mounted therein;

Fig. 5 is a transverse sectional elevation, taken along the line 5—5 in Fig. 4;

Fig. 6 is an enlarged sectional elevation, taken 35 along the line 6—6 in Fig. 5, and

Fig. 7 is a perspective view of the locking ring.

Referring to Figs. 1 to 3, I have shown a portion of a ring rail 10 having a circular opening 11 to receive a ring 12. In Figs. 1 to 3 the ring 40 12 is shown as a vertical twister ring having a cylindrical outer surface 14 adapted to fit snugly in the opening 11 in the ring rail 10. The ring 12 also has an external annular flange 15 adapted to rest on the upper surface of the rail 10 and 45 thus position the ring 12 vertically.

The cylindrical outer surface 14 of the ring 12 is provided with an annular concave groove 20, the major portion of which is below the bottom of the ring rail 10 when the ring 12 is in the position shown in Fig. 3.

50 A locking ring 22 is formed of spring steel wire or other similar material and preferably has the shape indicated in perspective in Fig. 7 and is of such diameter that when snapped over the

lower portion of the ring below the ring rail it will firmly seat itself in the groove 20.

An end portion 23 of the locking ring 22 is outwardly and downwardly offset to provide for convenient removal of the locking ring when desired.

In order that the ring 12 may be held firmly seated in the ring rail 10, it is desirable that the locking ring 22 should be wedged between the lower surface of the ring rail 10 and the lower 10 edge of the groove 20, as clearly shown in Fig. 3. It is also desirable that the locking ring should not "bottom" in the groove 20, as in that case the wedging action of the locking ring may be lost.

Consequently, the groove 20 should be so located with respect to the thickness of the rail 10 and the cross-section of the locking ring that the distance between the lower edge of the groove and the under face of the rail will be slightly less 20 than the cross section diameter of the locking ring.

The construction above described has been found by actual test to very firmly retain a ring in a ring holder and the locking ring may also be 25 quickly and easily removed to release the spinning or twister ring when desired.

Particular attention is called to the very simple additional operation on the ring 12 which is necessary to adapt the same to the purposes of my 30 invention. It is merely necessary to provide the cylindrical outer surface 14 of the ring 12 with the annular groove 20. No extra or additional operation whatever is necessary on the ring rail 10, the ring 12 being seated directly in the usual 35 circular opening cut straight through the ring rail to receive the ring.

In Figs. 4, 5, and 6 I have shown the adaptation of my invention to a construction in which a spinning ring 30 is mounted in a ring holder 40 31 having a cylindrical outer surface 32 adapted to fit in a circular opening 33 in a sheet metal ring rail 34. An annular groove 35 is provided in the cylindrical surface 32 and is so positioned that the locking ring 36 will maintain the parts 45 in the position shown in Fig. 6, with the ring wedged between the under surface of the ring rail 34 and the lower edge of the groove 35, all as previously described.

The second form of my invention possesses all 50 of the advantages of simplicity and reliability which are found in the form shown in Figs. 1 to 3.

Where the term "spinning ring" occurs in the claims, it is to be understood as including rings used in both spinning and twisting operations.

Having thus described my invention and the advantages thereof, I do not wish to be limited to the details herein disclosed, otherwise than as set forth in the claims, but what I claim is:—

- 5 1. In a spinning frame, a sheet metal ring rail having a series of circular openings having straight side walls, a spinning ring for each opening having a cylindrical outer surface associated therewith and having an external supporting shoulder above said cylindrical surface, and a locking ring for each spinning ring comprising a resilient open wire circle, the cylindrical outer surface associated with said spinning ring having an annular groove for said locking 10 ring, and the lower edge of said groove being at a slightly less distance from the bottom of said ring rail than the diameter of the wire forming said locking ring, whereby said spinning ring is tightly held from upward movement in said ring rail but said locking ring is not seated in said groove.
- 15 2. In a spinning frame, a sheet metal ring rail having a series of circular openings having straight side walls, a spinning ring for each opening having a cylindrical outer surface and having an external supporting shoulder above said cylindrical surface, and a locking ring for each

spinning ring comprising a resilient open wire circle, the cylindrical outer surface of said spinning ring having an annular groove for said locking ring, and the lower edge of said groove being at a slightly less distance from the bottom of said ring rail than the diameter of the wire forming said locking ring, whereby said spinning ring is tightly held from upward movement in said ring rail but said locking ring is not seated in said groove.

5

- 10 3. In a spinning frame, a sheet metal ring rail having a series of circular openings having straight side walls, a ring and ring holder for each opening, each ring holder having a cylindrical outer surface and having an external supporting shoulder above said cylindrical surface, and a locking ring for each holder comprising a resilient open wire circle, the cylindrical outer surface of said holder having an annular groove for said locking ring, and said locking ring being 15 slightly greater in diameter than the distance from the bottom of said ring rail to the lower edge of said groove, said locking ring being wedged between the lower edge of said groove and the under side of said ring rail but not seating in 20 said groove.
- 15 25

GEORGE WEST.
